(57) CLAIM

The ornamental design for a throwing hatchet, as shown and described.

DESCRIPTION

FIG. 1 is a perspective view of a first embodiment of a throwing hatchet according to the new design;

FIG. 2 is a left-side elevational view thereof;

FIG. 3 is a right-side elevational view thereof;

FIG. 4 is a front plan view thereof;

FIG. 5 is a back plan view thereof;

FIG. 6 is a top plan view thereof; and,

FIG. 7 is a bottom plan view thereof.

The broken lines of FIGS. 1-7 illustrate portions of the throwing hatchet that form no part of the claimed design.
